UNITED STATES PATENT OFFICE.

EUGÈNE O DAM, OF PARIS, FRANCE

CENTRIFUGAL PULVERIZING MILL

Application filed July 8, 1919. Serial No. 309,474.

To all whom it may concern:

Be it known that I, EUGÈNE O DAM, a citizen of the Republic of France, residing at 131 Rue d'Avron, Paris, France, have invented a new and useful Centrifugal Pulverizing Mill; and I do hereby declare that the following is a full, clear, and exact description of the invention, which will enable others skilled in the art to which it appertains to make and use the same.

This invention relates to an apparatus which effects the reduction to powder of granulated materials by acting upon them between balls having a rolling movement in suitable paths or races.

According to the invention I advantageously employ a ball grinding mill in which the granulated material to be pulverized in a cold state is introduced at the centre and caused to move outwardly under centrifugal force, thereby producing a constant flow of the said material which is pulverized in its passage between the balls and the channels or races in which they run.

To enable the invention to be understood I will describe the same by reference to the accompanying drawing which illustrates the improved method and the manner of carrying the same into effect.

Figure 1 is a diagrammatic elevation showing the principle of the invention.

Figure 2 is a plan of Figure 1.

Figure 3 is a vertical section of an apparatus constructed according to the invention.

Referring to Figures 1 and 2 *a* is the upper plate of the apparatus provided with a central tubular reservoir *b*, which serves for the introduction and guidance of the substances to be pulverized. The lower plate *c* is provided with a central conical part *d*, of slight inclination which facilitates the flow of the said substances.

This flow is effected by turning one of the plates, for example the plate *a*, in the direction of the arrow *f* (Figure 2). The substances within the circular space *e* are directed slowly towards the periphery and consequently pass between the balls *f* and the channels or races in which they run where they are subjected to a suitable pressure and crushed and whence they pass to the periphery *g*.

In the complete construction shown in Figure 3 the substances operated on are

caused to pass into successive superposed ball races mounted on a vertical shaft.

In Figure 3 *h*¹ indicates the first compartment into which are introduced through the opening *i*¹ the substances to be pulverized which follow the path indicated by the arrows *f*⁵ and pass to the first set of balls *u*¹, on leaving which they follow the path indicated by the arrows *f*⁶ into the second compartment *h*² whence they pass to the second set of balls *u*², on leaving which they pass into a conduit *i*² whence they travel to the inlet opening of a third compartment such as *h*¹. The number of superposed chambers employed may be varied according to the treatment to be effected.

The bottoms of these different compartments are of a funnel-like form being equivalents of the form of reservoir *b* shown in Figs. 1 and 2 and are traversed centrally by a vertical shaft *p* which communicates movement to a number of ball grinding devices. In the grinding device *u*¹ the lower part is actuated by a key *v* upon which it slides with slight frictional contact. In the second grinding device *u*², the upper part is actuated by a cross piece *r*¹ driven in the same manner as the first named device. The two free parts are held apart by a spring *s*¹ which thus exerts an equal pressure upon both grinding devices.

In each embodiment of the invention a charge of material to be ground is held in an upright receiver or reservoir, so that its weight feeds it downward within the circle of balls and outwardly to enter between the balls and the channels or races. Whether this reservoir is stationary or rotative, it holds what may aptly be designated as a static charge of the material to be ground.

It will be obvious that the devices described may include all the accessories generally known and employed therewith, particularly means for lubricating the moving parts.

It should be further understood that the arrangements described are shown by way of example only and may be varied without departing from the scope of the invention.

Claims:

1. A centrifugal ball mill, comprising a vertical shaft and two rings of balls, with stationary race members above the upper balls and below the lower balls and revolv-

ing race members having rotative engagement with said shaft, and a spring pressing said revolving members in contrary directions against their respective balls.

5. 2. A mill according to claim 1, the casing having a conical guiding portion for receiving the material discharged centrifugally from the upper ring of balls and directing it centrally through the lower race mem-

ber to feed it within the lower ring of 10 balls.

In witness whereof I have hereunto signed my name in the presence of two subscribing witnesses.

EUGÈNE ODAM.

Witness:

CHAS. P. PRESSLY.
